(57) **CLAIM**

We claim the ornamental design for a rotatable bird feeder-planter, as shown and described.

DESCRIPTION

FIG. 1. is a perspective view of a rotatable bird feeder-planter showing our new design, the broken lines shown are for illustrative purposes only and form no part of the claimed design;

FIG. 2. Is a right side elevational view of our rotatable bird feeder-planter shown in FIG. 1 with the left side elevational view being a substantial mirror image;

FIG. 3. Is a top view thereof; and,

FIG. 4. Is a front view thereof with the rear view being a substantial mirror image thereof.
